FOLDING IRONING BOARD

Vernon C. Wear, Santa Monica, Calif., assignor
to Roxton C. McKinnie, Santa Monica, Calif.

Application May 26, 1951, Serial No. 228,439

8 Claims. (Cl. 38—121)

1

This invention relates to folding ironing boards, and more particularly to those of the type that are so constructed that they can be set up for use optionally at any one of several different heights so as to offer the greatest convenience for use by persons of different stature, as well as under different circumstances of use, as, for example, when the operator is either sitting or standing.

The present invention, therefore, embodies improvements over the folding ironing boards disclosed in co-pending applications, Serial Numbers 767,976, now Patent No. 2,596,267, dated May 13, 1952 and 33,856, filed, respectively on August 11, 1947, and June 18, 1948, as well as over that disclosed in abandoned application, Serial No. 704,641, filed October 21, 1946, by Roxton C. McKinnie, the assignee of the present application.

An object of my present invention is to provide, in a folding ironing board of the general class described, an improved and simplified latch for retaining the body, or work-supporting element, of the ironing board at any elevation which might be selected by the operator, which latch is unusually strong and durable, simple and economical, highly positive and dependable, and operable with extreme ease in effecting either its engagement or release.

A further object is to provide, in an ironing board of the folding type, the construction of which is characterized by a pair of crossed leg members, one of which is pivoted to the under surface of the body portion, and the other of which is connected to the body portion for both pivotal and sliding movement with respect thereto, both leg members being pivotally interconnected where they intersect each other, improvements in all three of the mentioned points of attachment and interconnection, whereby unusual strength and rigidity are attained without any material increase in cost as compared with more conventional corresponding construction.

A further object of the invention in this same connection is to design the improved means for connecting the leg members to the body portion and for interconnecting the crossed leg members where they intersect, in such manner that wooden legs can be employed rather than the metal legs more commonly employed in ironing boards of this general type, without any sacrifice in strength, rigidity, durability, or ease and convenience of either the use of the ironing board or its adjustment to or from its folded or col-

2

apsed arrangement, or from one elevational adjustment to another.

The invention possesses other objects and features of advantage, some of which, with the foregoing, will be set forth in the following description of the preferred forms of my invention which are illustrated in the drawings accompanying and forming part of the specification. It is to be understood that I do not limit myself to the showing made by the said drawings and description, as I may adopt variations of the preferred forms within the scope of my invention as set forth in the claims.

Referring to the drawings:

15 Figure 1 is an underneath perspective view of a folding and adjustable ironing board incorporating principles of the present invention.

Figure 2 is an enlarged detail view in compound section, the planes of section being indicated by the lines 2—2 of Fig. 1 and the direction of view by the arrows. Portions of the figure are broken away to reduce its size.

Figure 3 is a view similar to Fig. 2, but with the planes of section indicated by the lines 3—3 of Fig. 1.

Figure 4 is a longitudinal, medial sectional view taken through the single leg member of the ironing board of Fig. 1 to show details of construction of the latch mechanism. The plane of section is indicated by the lines 4—4 of Fig. 1 and the direction of view by the arrows.

Figure 5 is a still more highly enlarged view in transverse section taken upon the line 5—5 of Fig. 4, with the direction of view as indicated.

Figure 6 is a compound sectional view taken transversely through the single leg and longitudinally along one of the pair of legs as indicated by the lines 6—6 of Fig. 1 and with the direction of view as indicated by the arrows.

Figure 7 is a view similar to Fig. 1, but showing a modified form of construction.

Figure 8 is an elevational view of the under surface of the board with the legs in their collapsed or folded relation.

Figure 9 is a view similar to Fig. 4, but with its plane of section indicated by the lines 9—9 of Fig. 7 and the direction of view by the arrows.

Referring first to that modification of my improved ironing board which is illustrated in Figures 1 to 6, inclusive, there is provided a body portion 11 preferably of conventional size and shape corresponding to the usual design of ironing board and formed of any suitable, rigid material. In the figures, the body portion 11 is illustrated as being composed of wood, although

it is to be understood that other types of body portion, such as expanded metal lath or sheet aluminum may be employed without departing from the essence of the present invention.

The body portion 11 is adapted to be supported at any of a plurality of optionally selectable elevations by a pair of crossed leg members 12 and 13 respective, the former comprising a single leg 14 and the latter comprising a pair of legs 16 extending in a common plane and flaring, at least throughout a substantial portion of their length, so that their lower ends are more widely separated in that plane than are their upper ends, thereby making for a greater degree of lateral stability of the ironing board that would be provided were the two legs 16 parallel to each other.

The two leg members 12 and 13 are disposed in angular relationship with respect to the body portion 11 and also with respect to each other, and are so associated that the single leg 14 of the member 12 intersects the plane of the legs 16 of the other leg member 13, passing between the two legs 16 to both of which it is pivotally interconnected at the location of such intersection as by a pivot pin construction to be described in greater detail hereinbelow.

The upper end of the single leg 14 of the member 12 is attached to the under surface of the body portion 11 for pivotal motion with respect thereto about an axis extending transversely of the body portion 11 and adjacent one end 21 of the body portion 11. The details of construction of the means for establishing such pivotal connection constitute one of the elements of the present invention. It comprises an elongated bracket 22 secured rigidly with the under surface of the body portion 11 as by a plurality of rivets 23 and in position extending transversely of the body portion. Each end of the bracket 22 is turned downwards to provide downwardly extending legs 24 spaced apart a distance substantially greater than the thickness of the single leg 14 through the upper end of which a pivot pin 26 extends, the ends of this pivot pin 26 being seated within the lugs 24. The pivot pin 26 also extends through two spacer tubes 27, one on each side of the leg 14, with the result that the tubes 27 operate to maintain the upper end of the leg 14 centered between the two lugs 24 and, therefore, under the longitudinal center line of the body portion 21. Preferably, a washer 28 is interposed between each of the two spacer tubes 27 and the associated side face of the leg 14 so as to protect the relatively soft wood of the leg 14 from the harder material of the metal spacer tube 27.

A pair of angular braces 29 are also provided, each having at its upper end a flange 31 through which the pivot pin 26 extends and which is seated between the outer end of the associated spacer tube 27 and the associated lug 24. The lower ends of the braces 29 also are provided with flanges 32, both of which engage the leg 14 on opposite faces thereof and at a substantial distance below the location of the pivot pin 26. Preferably, both braces 29 are rigidly secured to the leg 14 by a single rivet 33 or other suitable fastening means, extending through the leg 14 and through both flanges 32.

The relatively great distance between the two lugs 24 and the bracing effect obtained by the hereinabove described construction and arrangement of the braces 29 imparts to the body portion 21 the degree of rigidity and resistance to lateral rocking motion with respect to the leg 14 far greater than might be expected from any

other method of pivotally connecting the relatively narrow leg member 12 to the body portion 11.

The pivotal interconnection between the two leg members 12 and 13 hereinabove broadly referred to, comprises a pivot pin 36 which extends through both legs 16 of the leg member 13 and also through the single leg 14 of the leg member 12. As in the previously described pivotal connection, this pivot pin also carries a spacer tube 37 on each side of the single leg 14 and holding it centered within the space between the two legs 16 which space is substantially greater than the corresponding dimension of the single leg 14. Here again washers 38 are preferably employed to protect the relatively soft wood of the leg 14 from the harder material of the metal spacer tubes 37.

The upper end of the other leg member 13 is connected to the under surface of the body portion 11, not only for pivotal movement, but also for sliding movement longitudinally of the body portion 11, thus making allowance for the decrease in distance between the upper end of the leg members 12 and 13 as they are swung downwards from the body 11 and in pivotal movement with respect to each other about the axis of their interconnecting pivot pin 36. For this purpose, a pair of spaced parallel channel members 46 are secured to the under surface of the body 11 adjacent its other end 47 which preferably is tapered and rounded in accordance with conventional ironing board design. The two channels 46 extend longitudinally with respect to the body 11 and are disposed in opposed relation opening toward each other so that a bar 48 preferably of circular cross-section can extend between the two channels 46 with one end of the bar 48 slidably and pivotally disposed within each of the two channels, as is best illustrated in Fig. 3. Means are provided for connecting the upper end of the leg member 13 to the bar 48, comprising a pair of spaced plates 49, both of which are welded or otherwise rigidly secured tangentially to the bar 48 along the extreme upper edges of the plates 49. Each plate 49 is rigidly secured to one of the legs 16 of the member 13, as by a rivet 51 extending through that leg adjacent its upper end and through the plate 49. Hence, each plate 49 engages its associated leg 16 along only one face thereof. This type of connection between the legs 16 and the bar 48 is one of the details which permits the use of wooden legs rather than the more commonly employed metal, inasmuch as the downwardly extending plates 49 permit the rivets which pass through the legs 16 to be situated far enough from the associated ends of the legs to obviate the tendency which otherwise would be present for the wood to split and thus release the rivets 51 from the legs. Nevertheless, the bar 48 is situated substantially with its axis lying within the plane of the extreme ends of the legs 16, thus avoiding any interference with downward swinging movements of the legs 16 with respect to the body 11 which would develop if the upper ends of the legs 16 were to project for any material distance beyond the pivot bar 48, as can best be understood by reference to Fig. 3.

Each of the legs 16 of the pair of legs which comprise the member 13 comprises an upper portion 56 and a lower portion 57 rigidly interconnected by a tubular metal sleeve 58. The upper portions 56 of the two legs 16 are parallel to each other, whereas the lower portions 57 flare down-

wards and away from each other, with the result that their lower ends are materially more widely separated than are the upper portions 56 of the legs 16, thus adding very materially to the latter stability with which the leg member 13 supports the body portion 11. The tubular metal sleeves 58, therefore, contribute to the efficiency of the present invention in permitting the use of wooden legs each of which is not straight throughout its entire length. The lower end of the upper leg portion 56 of each leg 16 is rigidly seated within a socket portion 61 which comprises the upper end of the associated sleeve 58; and the upper end of the lower leg portion 57 is similarly seated within a socket 62 which comprises the lower end of the sleeve. Rivets 63 or other suitable type of fastening means assist in maintaining such seating of the associated ends of the portions 56 and 57 within their respective sockets 61 and 62. The fact that the upper portions 56 and the associated sockets 62 of their sleeves 58 facilitates construction of the pivotal interconnection between the leg members 12 and 13 since by positioning the holes in the legs 16 and 17 through which the ends of the pivot pin 36 extend, in the sockets 61, which are parallel to each other rather than in the sockets 62 which are disposed obliquely with respect to each other, it is made possible to drill the holes through a diameter of the sockets 61 and perpendicular to their major access rather than obliquely through the sockets as would be necessary were the holes to be drilled through the outwardly flaring portions of the sleeves 58 inasmuch as it is preferable that the pivot pin 36 be straight throughout its entire length.

Means are provided for releasably securing the leg members 12 and 13 in whatever degree of angularity with respect to each other as is necessary to attain the support of the body portion 21 at the elevation desired by the operator. For this purpose a latch mechanism indicated in its entirety at 71 is provided. As is most clearly illustrated in Figures 4 and 5, this latch mechanism 71 comprises an elongated relatively thin and narrow blade 72 having one end 73 seated within a longitudinally extending slot 74 in the upper face of the single leg 14. A pivot pin 76 driven through the leg 14 in such position that it intersects the slot 74 adjacent the upper end of the latter, serves to secure the blade 72 in position. The blade 72 inclines outwardly of the slot from its pivot pin 76 so as to dispose notches 77 in its upper edge in position to be selectively engaged by a detent preferably in the form of a pin 78 carried by a collar 79 encircling and sliding longitudinally along both the leg 14 and the blade 72. This collar 79 comprises a substantially circular portion 81 which almost completely encircles the leg 14, and a radially extending latch portion 82 having parallel sides 83 between which the pin 78 extends. The end 84 of the blade 72 remote from the pivot pin 76 is urged outwardly from the slot 74 as by a coil spring 86 under compression between the inner edge of the blade 72 and a socket or recess 87 in the bottom of the slot 74. A strap 88 rigidly secured to the leg 14 and extending therefrom around the blade 72 adjacent its free end 84 limits outward motion of the blade 72 regardless of the position of adjustment of the collar 79. The notches 77 are distributed at spaced intervals along the outer end of the blade 72 with the result that the collar 79 may be anchored rigidly in selected position of sliding movement along the leg 14 as

determined by which one of the several notches 77 the pin 78 is seated within, as illustrated in Figure 4.

The collar 79 is connected as by rods 89 to preferably both of the legs 16 of the pair of legs which comprise the member 13. The connections of the rods 89 to the collar 79 and also the connections of the rods 89 to the legs 16 are of a pivotal nature so as to avoid restriction of the necessary motion between the parts. Consequently, as the leg members 12 and 13 are swung upwards toward the body portion 11 causing the angularity between the lower portions of the leg members 12 and 13 to increase, the rods 89 will draw the collar 79 upwards along the leg 14, provided of course the blade 72 has been depressed against the action of the spring far enough to release the pin 78 from whichever one of the notches 77 within which it may have been engaged.

The parts are so proportioned and arranged that the latch 71 is mounted at the lower end of the leg 14 with the free end 84 of the blade 72 closely adjacent the extreme lower end of the leg, as is best shown in Fig. 1. In this position it is conveniently accessible to the operator's foot, with the result that when it is desired to change the elevation at which the body 11 is supported, all that the operator has to do is to step upon the end 84 of the blade which will cause the blade to pivot downwards more deeply into the slot 74 and thereby withdraw it from engagement with the pin 78 of the slidable collar 79. The latter is then freed for sliding movement along the leg with the result that the operator can then either raise or lower the body 11 to whatever new position of adjustment may be desired. However, under most circumstances of use, the most convenient method of collapsing the board, as for storage, is to stand the board upon its end 21 before the leg members 12 and 13 are swung toward the body 11. The operator can then grasp the tapered end 47 of the body 11 in one hand and the end of the leg 14 in the other, and by depressing the end 84 of the blade 72 then release the collar 79 from its engagement with the blade, with the result that the board can then be collapsed simply by drawing the end of the leg 14 toward the end 47 of the body 11.

When completely collapsed, the two leg members 12 and 13 will occupy a common plane, i. e., the single leg 14 will lie between the two legs 16 of the member 13 closely adjacent and parallel to the under surface of the body 11. This is another advantage deriving from the hereinabove described means for connecting the upper ends of the legs 13 to the pivotal and sliding bar 48 which, being at one side of the legs 16 rather than passing diametrically through them permits the legs 16 to assume the described position closely adjacent and parallel to the under surface of the body 11.

Figures 7, 8, and 9 illustrate a modified form of ironing board embodying principles of the present invention. As in the previously described modification, this form also comprises a body portion 101 and leg members 112 and 113, the former comprising a single leg 114 and the latter a pair of legs 116. The leg 114 is similar to the single leg of the previously described modification and is similarly pivotally mounted upon the under surface of the body 101, i. e., by means of a bracket 122 having down turned lugs 124 supporting a pivot pin 126 upon which tubular spacers 127 and washers 128 maintain the upper end of

the single leg 114 centered between the lugs 124. Braces 129 also are employed which are constructed and which function similarly to the braces 29 of the previously described modification.

The other leg member 113, on the other hand, is considerably different from the leg member 13 in that each of its legs 116 is straight and of one piece construction, preferably a wooden pole of considerable length. Consequently, the portion of each leg 116 through which extends the pivot pin 136 which interconnects the two leg members 112 and 113 must extend through a hole in each leg 116 which is oblique with respect to the major axis of that leg, as best seen in Fig. 8.

Moreover, inasmuch as the legs 116 are straight and diverged downwardly from the body portion 101, the portions of the legs 116 through which the pivot pin 136 extends are more widely separated than are the corresponding portions of the legs 16 of the first described modification, with the result that the pivot pin 136 is substantially longer than the pivot pin 36 previously described. Correspondingly, the spacer tubes 137 on the pivot pin 136 and which operate to center the leg 114 between the two legs 116 are also longer than are the spacer tubes 37 of the first described modification.

However, the most pronounced difference between the pivotal interconnection between the two leg members of the modification illustrated in Figures 7, 8, and 9, as compared to that of the previously described modification, lies in the incorporation of two pairs of braces 161 and 162 with the single leg 114 and with the pair of legs 116, respectively. The first mentioned pair of braces 161 have flanges 163 on their lower ends (i. e., the ends thereof which are lowermost when the ironing board is in its operative arrangement, as in Fig. 7) which are secured rigidly on opposite sides of the single leg 114 below the pivot pin 136. Similarly, flanges 164 on the upper ends of the braces 161 are engaged upon the pivot pin 136 between the spacer tubes 137 and the respectively associated legs 116, i. e., in engagement with the outer ends of the spacer tubes 137.

The braces 162, on the other hand, have flanges 171 rigidly secured to the legs 116 below the pivot pin 136 whence the braces 162 incline upwardly and inwardly so that flanges 172 on their upper ends are engaged on the pivot pin 136 between the inner ends of the spacer tubes 137 and the single leg 114.

In this modification, the means for slidably and pivotally connecting the upper end of the leg member 113 to the under surface of the body portion 101 is preferably the same as that described in connection with the previous modification, i. e., through the expedient of plates 149 extending rigidly downwards from a transversely extending pivot bar 148 and engaging the faces of the legs 116 which are closest to the under side of the body 101 when the legs are collapsed. The ends of the bar 148 are similarly engaged within opposed inwardly opening channels 146 rigidly secured in spaced parallel relation extending longitudinally of the body portion 101.

The latch member 171, however, at the lower end of the leg 114 is distinguished from the latch 11 previously described in that its blade 172 is provided with a plurality of spaced upwardly extending rectangular teeth 174 selectively and removably receivable within a hole 174 in the top portion of a collar 176 slidable upon the leg 114 and embracing the blade 172. In this modification of the latch 171, instead of employing a strap

to limit outward motion of the blade 172 is urged by a compression spring 177 and about its pivot pin 178, reliance is placed in the collar 176 to perform that function. An enlargement 179 on the lower end of the blade 172 is always conveniently accessible to the operator for retraction of the blade 172 into that position in which all of its teeth 174 are withdrawn from the path of movement of the collar 176 as the latter slides along the leg 114 as urged by rods 189 which connect the collar 176 to the legs 116 at points between the lower ends of the legs 116 and the pivot pin 136.

I claim:

1. In a folding and vertically adjustable ironing board, a body, a leg member supporting each end of said body, each of said leg members extending obliquely downwards from said body in a plane intersecting the plane of the other of said leg members, one of said leg members comprising a pair of legs and the other comprising a single leg extending between said pair of legs, a bracket secured to the under surface of said body and extending transversely thereof adjacent one end of said body and comprising a downwardly extending lug at each end thereof, the distance between said lugs being substantially greater than the thickness of said single leg measured in the same direction, a pivot pin carried by said lugs and extending through said single leg adjacent the upper end thereof, and a spacing tube on said pivot pin on each side of said single leg and holding it centered between said lugs, means pivotally and slidably connecting the upper end of the other of said leg members to said body, means pivotally interconnecting said leg members for movement with respect to each other about an axis within the intersection of said planes, and a latch for releasably retaining said leg members at selected angularity with respect to each other.

2. In a folding and vertically adjustable ironing board, a body, a leg member supporting each end of said body, each of said leg members extending obliquely downwards from said body in a plane intersecting the plane of the other of said leg members, one of said leg members comprising a pair of legs and the other comprising a single leg extending between said pair of legs, a bracket secured to the under surface of said body and extending transversely thereof adjacent one end of said body and comprising a downwardly extending lug at each end thereof, the distance between said lugs being substantially greater than the thickness of said single leg measured in the same direction, a pivot pin carried by said lugs and extending through said single leg adjacent the upper end thereof, a spacing tube on said pivot pin on each side of said single leg, a brace rigidly secured upon each side of said single leg at a point spaced from said pivot pin, each of said braces extending obliquely upwards and outwards and the upper end of each of said braces being mounted upon said pivot pin between the associated lug and the outer end of the associated spacing tube, means pivotally and slidably connecting the other of said leg members to said body, means pivotally interconnecting said leg members for movement with respect to each other about an axis within the intersection of said planes, and a latch for releasably retaining said leg members at selected angularity with respect to each other.

3. In a folding and vertically adjustable ironing board, a body, a leg member supporting each end of said body, each of said leg members ex-

tending obliquely downwards from said body in a plane intersecting the plane of the other of said leg members, one of said leg members comprising a pair of legs and the other comprising a single leg extending between said pair of legs, means pivotally connecting the upper end of one of said leg members to said body, means pivotally and slidably connecting the upper end of the other of said leg members to said body comprising a pair of spaced, parallel channels secured to the under surface of said body and extending longitudinally thereof in opposed relation opening toward each other, a bar disposed with one of its ends slidably engaged within each of said channels, said bar being pivotally movable about its own axis with respect to said channels, and a plate rigid with said bar and extending downwards therefrom and rigidly secured to a face of said other leg member, means pivotally interconnecting said leg members for movement with respect to each other about an axis within the intersection of said planes, and a latch for releasably retaining said leg members at selected angularity with respect to each other.

4. In a folding and vertically adjustable ironing board, a body, a leg member supporting each end of said body, each of said leg members extending obliquely downwards from said body in a plane intersecting the plane of the other of said leg members, means pivotally connecting the upper end of one of said leg members to said body, means pivotally and slidably connecting the upper end of the other of said leg members to said body, one of said leg members comprising a pair of legs and the other comprising a single leg extending between said pair of legs, each of said legs of said pair of legs comprising an upper portion extending downwardly from said body in a plane substantially perpendicular to said body, an angulated connecting sleeve comprising an upper socket within which the lower end of the associated upper leg portion is rigidly seated and a lower socket rigid therewith and opening in a downwardly and outwardly inclined direction, and a lower leg portion rigidly seated within said lower socket of the associated sleeve, means pivotally interconnecting said leg members for movement with respect to each other about an axis within the intersection of said planes, and a latch for releasably retaining said leg members at selected angularity with respect to each other.

5. In a folding and vertically adjustable ironing board, a body, a leg member supporting each end of said body, each of said leg members extending obliquely downwards from said body in a plane intersecting the plane of the other of said leg members, means pivotally connecting the upper end of one of said leg members to said body, means pivotally and slidably connecting the upper end of the other of said leg members to said body comprising a pair of spaced, parallel channels secured to the under surface of said body and extending longitudinally thereof in opposed relation opening toward each other, a bar disposed with one of its ends slidably engaged within each of said channels, said bar being pivotally movable about its own axis with respect to said channels, and a plate rigid with said bar and extending downwards therefrom and rigidly secured to a face of said other leg member, one of said leg members comprising a pair of legs and the other comprising a single leg extending between said pair of legs, each of said legs of said pair of legs comprising an upper portion extend-

ing downwardly from said body in a plane substantially perpendicular to said body, an angulated connecting sleeve comprising an upper socket within which the lower end of the associated upper leg portion is rigidly seated and a lower socket rigid therewith and opening in a downwardly and outwardly inclined direction, and a lower leg portion rigidly seated within said lower socket of the associated sleeve, means pivotally interconnecting said leg members for movement with respect to each other about an axis within the intersection of said planes, and a latch for releasably retaining said leg members at selected angularity with respect to each other.

6. In a folding and vertically adjustable ironing board, a body, a leg member supporting each end of said body, each of said leg members extending obliquely downwards from said body in a plane intersecting the plane of the other of said leg members, means pivotally connecting the upper end of one of said leg members to said body, means pivotally and slidably connecting the upper end of the other of said leg members to said body, one of said leg members comprising a pair of legs and the other comprising a single leg extending between said pair of legs, each of said legs of said pair of legs comprising an upper portion extending downwardly from said body in a plane substantially perpendicular to said body, an angulated connecting sleeve comprising an upper socket within which the lower end of the associated upper leg portion is rigidly seated and a lower socket rigid therewith and opening in a downwardly and outwardly inclined direction, and a lower leg portion rigidly seated within said lower socket of the associated sleeve, means pivotally interconnecting said leg members for movement with respect to each other about an axis within the intersection of said planes, said interconnecting means comprising a straight pivot pin extending through said upper sockets of both of said angulated connecting sleeves to interconnect said legs of said pair and through said single leg, and a spacer tube on said pivot pin on each side of said single leg and holding it centered between said legs of said pair of legs, and a latch for releasably retaining said leg members at selected angularity with respect to each other.

7. In a folding and vertically adjustable ironing board, a body, a leg member supporting each end of said body, each of said leg members extending obliquely downwards from said body in a plane intersecting the plane of the other of said leg members, means pivotally connecting the upper end of one of said leg members to said body, means pivotally and slidably connecting the upper end of the other of said leg members of said body, one of said leg members comprising a pair of legs and the other comprising a single leg extending between said pair of legs, means pivotally interconnecting said leg members for movement with respect to each other about an axis within the intersection of said planes, said interconnecting means comprising a straight pivot pin extending between said legs of said pair and through said single leg, a spacer tube on said pivot pin on each side of said single leg and holding it centered between said legs of said pair of legs, a pair of braces rigid at their lower ends with said single leg below said leg member interconnecting means and each engaged at its upper end between the outer end of one of said spacer tubes and the associated leg of said pair of legs, 75 and a second pair of braces, each secured at its

11

lower end to one of said pair of legs below said leg member interconnecting means and engaged at its upper end upon said pivot pin between the inner end of the associated spacing tube of said pair of legs and said single leg, and a latch for releasably retaining said leg members at selected angularity with respect to each other.

8. In a folding and vertically adjustable ironing board, a body, a leg member supporting each end of said body, each of said leg members extending obliquely downwards from said body in a plane intersecting the plane of the other of said leg members, means pivotally connecting the upper end of one of said leg members to said body, means pivotally and slidably connecting the upper end of the other of said leg members to said body, one of said leg members comprising a pair of legs and the other comprising a single leg extending between said pair of legs, each of said legs of said pair of legs being straight throughout its length and being disposed in downwardly and outwardly divergent relation to the other of said legs of said pair of legs whereby each of said legs of said pair of legs is spaced a substantial distance from said single leg, means pivotally interconnecting said leg members for movement with respect to each other about an axis within the intersection of said planes, said interconnecting means comprising a straight
